SCREEN FOR HAMMER MILLS

Frank Beverly, Coleman, Tex., assignor of one-half to Claud McClellan, Coleman, Tex.

Application April 27, 1939, Serial No. 270,417

1 Claim. (Cl. 83—11)

This invention relates to a screen for a hammer mill, and it is an object of the invention to provide a screen of this kind provided with means to increase the capacity of the mill by the grinding of feeds that would otherwise be thrown back to dry or which would ordinarily gum up or clog the mill.

Another object of the invention is to provide a screen with transversely disposed elements extending across the inner face of the screen to make the feed bounce and re-bounce whereby the hammers of the mill are given more hits at the feed during the operation of the mill and thereby materially increasing the output of the mill without any material increase in power.

The invention consists in the details of construction and in the combination and arrangement of the several parts of my improved screen for a hammer mill whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a fragmentary vertical sectional view taken through a hammer mill disclosing a screen constructed in accordance with an embodiment of my invention;

Figure 2 is a fragmentary view in plan of the inner face of the screen as herein disclosed;

Figure 3 is a view similar to Figure 2 illustrating another embodiment of the invention;

Figure 4 is a fragmentary sectional view taken circumferentially of the screen and illustrating another embodiment of the invention;

Figure 5 is a view in perspective of the bar illustrated in Figure 4, unapplied.

In the accompanying drawing, H denotes the upper portion of a rotor housing and which has associated therewith the usual top member T. Mounted as is well known within the housing H and the top member T when closed is the rotor R carrying the usual hammers D. The rotor R is to be driven in any manner desired and at a speed preferred. Discharging within the housing H is a conventional feed chute F.

As herein disclosed, the screen is cylindrical and comprises two substantially duplicate sections A, one being arranged within the top member T and the other within the housing H and

said sections when the top member T is closed surrounding and enclosing the rotor R together with the hammers D. The assembled sections A are circular in cross section and substantially concentric to the axial center of the rotor R.

In the embodiment of the invention as illustrated in Figure 1, each of the screen sections A is provided along its inner face with the bars 1. Each of these bars is substantially co-extensive in length with the length of the section A and said bar 1 is welded to the inner face of the section between adjacent rows of screen openings 2. The bar 1 is V-shaped in cross section with the apex thereof disposed inwardly from the section A and which apex a provides a sharp edge. The bars 1 are preferably equidistantly spaced in a direction circumferentially of a section A and are in parallelism.

The rotor R rotates in the direction indicated by the arrow b and as the feed stream delivered from the chute F is hit by the hammers D, the bars 1 will cause the grain to bounce and re-bounce thus preventing grain slipping around with the rotor. This continued bouncing of the grain, plus the sharp edges a in their coaction with the hammers, results in the grinding of substantially all of the grain, thereby greatly increasing the output of the mill. In other words, the particular construction of the screen as herein described is such as to materially reduce grain or feed that would have to be thrown back to dry or which would otherwise gum up or clog the mill and greatly reduce its output.

The bars 1 are made of hardened metal.

In the embodiment of my invention as particularly illustrated in Figure 3, bars 3 are welded or otherwise secured to the inner face of the screen section B and arranged in two rows side by side with the bars extending between adjacent openings 4 of the screen section B. The bars 3 of one row also alternate or stagger with respect to the bars 3 of the adjacent row.

In the embodiment of my invention as illustrated in Figures 4 and 5, the screen C has bolted thereto, as at 5, a readily removable angle bar 6. This bar 6 is also of a length co-extensive with the length of the screen section C and when applied has an upstanding flange 7, the upper portion of which is formed to provide a sharp edge 8.

From the foregoing description it is thought to be obvious that a screen for a hammer mill constructed in accordance with my invention is particularly well adapted for use by reason of the convenience and facility with which it may be

assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

10 I claim:

A cylindrical screen for a hammer mill having rows of openings at spaced points around the

screen, members carried by the screen and extending inwardly thereof, said members being disposed lengthwise of the screen and having their inner edges sharp, said members being spaced apart in a direction circumferentially of the screen with adjacent members in relatively close proximity, each of said members being positioned between adjacent rows of openings, each of said members being V-shaped in cross section with its apex inwardly disposed. 10

FRANK BEVERLY.
